UNITED STATES PATENT OFFICE.

WALTER E. CLIFFORD, OF HOPEDALE, MASSACHUSETTS, ASSIGNOR TO DRAPER COMPANY, OF HOPEDALE, MASSACHUSETTS, A CORPORATION OF MAINE.

APPARATUS FOR VENTING CORES.

No. 893,569.

Specification of Letters Patent.

Patented July 14, 1908.

Application filed January 15, 1908. Serial No. 410,898.

To all whom it may concern:

Be it known that I, WALTER E. CLIFFORD, a citizen of the United States, and resident of Hopedale, county of Worcester, State of Massachusetts, have invented an Improvement in Apparatus for Venting Cores, of which the following description, in connection with the accompanying drawing, is a specification, like letters on the drawing representing like parts.

This invention has for its object the production of apparatus for readily and quickly venting a gang or group of cores used in metal founding.

Where a large number of cores of a similar character are used they are formed in a core-box containing a large number of molds in which the cores are formed, and it is necessary to vent the cores so that the gases generated by the molten metal may escape without injury to the mold or the casting.

The venting of the core is usually performed by thrusting into it a thin rod or pin, and the present invention provides a simple apparatus whereby a gang or group of cores may be vented simultaneously, while they are in the core-box. This mode of procedure facilitates the core-making operation and is attended with no liability of damaging the core.

Figure 1 is a front elevation of a core-venting apparatus embodying one form of the present invention; Fig. 2 is a top plan view thereof.

In the present embodiment of the invention a flat, rectangular and preferably metallic plate 1 constitutes a base, Fig. 1, having a series of apertures 2, see dotted lines Fig. 1, formed therein, one for each of the venting pins 3. These venting pins are long, slight metal rods of suitable diameter to form the vents, and each one at its lower end loosely enters one of the holes 2 in the base, the upper ends of the pins being fixedly held in a carrier.

The carrier is shown in Fig. 2 as a rectangular frame 4 having a series of parallel longitudinal bars 5, strengthened by cross-bars or connections 6; the upper ends of the pins 3 being securely fixed in the bars, the number and relative position of the pins being determined by the number and position of the core molds in the core-box. Handles 7 are attached to the top of the carrier, at its op-

posite ends, to enable the apparatus to be carried about conveniently from place to place.

A stout guide-rod 8 is rigidly attached to the base 1 at the center thereof and is extended upward through a center hole in the crossed portions of two frames 9, 10, preferably made of strap metal and riveted to the carrier, the frames projecting some distance above the carrier as shown in Fig. 1.

Check-nuts 11 are screwed onto the upper end of the guide-rod, above the crossing of the frames, and a spiral spring 12 is coiled around the guide-rod between the base and the top of the frames, said spring normally holding the carrier and base separated, as in full lines Fig. 1. The check-nuts are adjusted so that the lower ends of the venting pins 3 will be housed within the base when the spring is expanded, the frames 9 and 10 serving to stiffen the guide-rod and the latter, with the pins 3, prevent any lateral displacement of the base and carrier.

In using the apparatus the base is set on top of the core-box with the gang of pins 3 over the upper ends of the cores therein, and the operator then grasps the handles 7 and presses the carrier steadily downward, the venting pins depending therefrom sliding through the base and into the cores, to form the vents therein. The dotted lines in Fig. 1 show the pins projected below the base, the corresponding position of the carrier being also shown in dotted lines.

In order to positively limit the operative movement toward the base adjustable stops 90 are provided, shown as threaded rods 13 passed through threaded holes in the frame 4 of the carrier, preferably diagonally opposite each other, each stop having a check-nut 14 and a milled or other head 15. The stops 95 are set at such a distance from the base as it is desired the venting pins shall enter the cores, so that when the pins have been projected the requisite distance the ends of the stop will engage the base and prevent further operative movement of the carrier. When the cores have been vented the carrier is released and it is elevated by expansion of the spring 12, thereby returning the apparatus to normal position, the ascent of the carrier 105 retracting the venting pins from the cores.

It will be manifest that the movement of the pins is direct and accurate, it is regulated

positively, by the means described, and said pins are withdrawn smoothly and without lateral movement, the apparatus enabling a gang or group of cores to be vented simultaneously.

Having fully described my invention, what I claim as new and desire to secure by Letters Patent is:—

1. In a portable core-venting apparatus, a carrier having attached to it a gang of depending pins adapted to enter the cores, an apertured base through which the free ends of the pins pass, said base being adapted to rest upon the top of a core-box, a guide-rod rigidly attached to the base at its center and loosely extended through the carrier, a spring normally separating the base and carrier, and means to limit the spring-induced separation of said parts and prevent withdrawal of the free ends of the pins from the base, downward pressure on the carrier compressing the spring and projecting the lower ends of the pins beyond the base and into a group of cores, to form vents therein.
2. In a core-venting apparatus, an apertured base, a carrier having a gang of depending venting pins longitudinally movable through the apertures in the base, separate means to guide the movement of the carrier toward the base, to project the pins beyond the base and into the cores, means to yieldingly separate said base and carrier, and adjustable means to positively limit the operative movement of the carrier to project the venting pins.
3. In a core-venting apparatus, an apertured base adapted to rest upon the top of a core-box, a carrier movable toward and from the base and having an attached group of venting pins extended slidably through the base, to pass into and form vents in the cores in a core-box, a spring interposed between the base and carrier, to lift the latter and retract the pins from the cores, means to limit the separation of the base and carrier, and adjustable stops on one of said parts to engage the other part and thereby limit move-

ment of the carrier to project the pins into the cores.

4. In a core-venting apparatus, a base adapted to rest upon the top of a core-box, a yieldingly-sustained carrier movable toward and from the base, a plurality of venting pins rigidly attached to the carrier and movable longitudinally through the base, to pass into the cores, when the carrier is depressed, means to limit movement of the carrier to retract the pins, and means to determine the extent to which the pins shall be projected beyond the base by operative movement of the carrier.

5. In a core-venting apparatus, a base adapted to rest upon the top of a core-box, a yieldingly-sustained carrier movable toward and from the base, a plurality of venting pins rigidly attached to the carrier and movable longitudinally through the base, to pass into the cores, when the carrier is depressed, means to limit movement of the carrier to retract the pins, threaded stops extended through the carrier, to engage the base and thereby limit the extent to which the pins shall be projected by operative movement of the carrier, and check-nuts to lock the stops when adjusted.

6. In a core-venting apparatus, a base adapted to rest upon the top of a multiple core-box, a carrier movable toward and from the base, a gang of venting pins mounted on the carrier and longitudinally movable through the base, to enter the cores and vent the same simultaneously when the carrier is depressed, and adjustable means to limit the movement of the carrier toward the base, to thereby limit the penetrative movement of the venting pins.

In testimony whereof, I have signed my name to this specification, in the presence of two subscribing witnesses.

WALTER E. CLIFFORD.
